UNITED STATES PATENT OFFICE.

EDWARD S. FITCH, OF WAYLAND, MICHIGAN.

NAME-HOLDER FOR MAIL-BOXES.

994,734.

Specification of Letters Patent. Patented June 13, 1911.

Application filed February 15, 1911. Serial No. 608,734

To all whom it may concern:

Be it known that I, EDWARD S. FITCH, a citizen of the United States, residing at Wayland, in the county of Allegan and State 5 of Michigan, have invented new and useful Improvements in Name-Holders for Mail-Boxes, of which the following is a specification.

The invention relates to letter holders, and 10 more particularly to the class of name holders and adjustable letters therefor.

The primary object of the invention is the provision of a holder of this character in which letters may be securely mounted to 15 designate the name of a person residing along a rural free delivery route, so that the mail box may conveniently show the number of the route and the name of the user of the said box.

20 Another object of the invention is the provision of a name holder in which the letters thereof may be readily and easily adjusted or removed therefrom for altering the name of the user of the box, and when 25 mounted in the holder will be securely held against longitudinal displacement therein, the initial letters of the name of such person being divided by means of members designating dots, each being formed of a face 30 plate mounted upon the head of a bolt member which serves to support said plate and also to secure the holder to the lid or cover of a rural free delivery mail box.

A further object of the invention is the 35 provision of a holder in which the letters designating the name of the user of the rural mail box are mounted in guides, which are pinched or contracted between said letters, so as to sustain the latter in their ad- 40 justed position and prevent them from be- coming displaced within the holder, it being understood of course that in lieu of the letters, other characters or numerals may be substituted.

45 A still further object of the invention is the provision of a holder of this character and the letters therefor which are simple in construction, and inexpensive in manufac- ture.

50 With these and other objects in view, the invention consists in the construction, com- bination and arrangement of parts, as will be hereinafter more fully described, illus- trated in the accompanying drawings, and 55 pointed out in the claim hereunto appended.

In the drawings: Figure 1 is a perspective

view of a mail box, showing the invention applied to its lid or cover. Fig. 2 is a fragmentary enlarged top plan view of the holder and the letters therefor mounted in 60 the same. Fig. 3 is a sectional view on the line 3—3 of Fig. 2. Fig. 4 is a sectional view on the line 4—4 of Fig. 2.

Similar reference characters indicate cor- 65 responding parts throughout the several views of the drawings.

Referring to the drawings by numerals, 5 designates the body and 6 the hinged lid or cover of a rural free delivery mail box, which is of the ordinary well-known con- 70 struction, and is merely shown for the pur- pose of illustrating the manner of mounting the name holder and the letters therefor, as will be hereinafter more fully described.

The name holder comprises a flat narrow 75 elongated base plate 7, preferably construct- ed from metal, although the same may be made from any other suitable material, should it be desired, and has its opposite ends cut to form rounded extremities 8. 80 However, these ends may be made square or any other desirable shape to add to the ornamentation of the holder. The opposite longitudinal edges of the base plate 7 are upbent and inturned to form guide flanges 85 9, overhanging the said base plate for a short distance at its opposite longitudinal edges, the said flanges being coextensive with the length of the plate 7, and slidably engaged therewith is a plurality of letters 90 10, the same being arranged to designate the name of the user of the mail box. These letters 10 are separated the required distance from each other, and thereafter the flanges 9 are instruck, as at 11, between the said 95 letters 10, so as to prevent the jamming to- gether or longitudinal displacement of the said letters after the same have been ad- justed in the holder, the instruck portions 11 of the flanges 9 contacting with the base 100 plate 7 and forming undulations in the said flanges 9 between the letters, thus locking the outer ends of the letters engaged in the guide flanges 9 to prevent displacement thereof longitudinally along the base plate 105 forming the holder therefor.

The base plate at opposite ends is pro- 110 vided with suitable openings through which are passed bolt members 12 which are also engaged in the lid or cover 6 of the mail box for the secure mounting of the base plate 7 exteriorly upon the same.

Between the initial letters or those designating the initial of the Christian and middle names of the user of the mail box are disposed bolt members, the same being passed through the base plate 7 and the lid or cover 6 of the box, thus serving as supplemental fasteners for the holder. The heads 14 of the bolt members 13 have soldered or otherwise secured thereto square-shaped plates 15 designating dots separating the initial letters of the name of a person using the mail box, which name is composed of a series of letters 10 by the proper arrangement thereof in the holder.

10 Each letter 10, for a greater portion of its length, is raised, so that the face of the letter will lie in a plane spaced from the base plate 7, while the ends of the said letter will be offset with respect to the raised portion 20 thereof for engagement in the guide flanges 9 of the holder. Thus, it will be seen that the initials and last name of a person formed by the letters will stand out boldly from the holder when the latter and the letters there- 25 in have been mounted upon the mail box. Also, it is to be understood that in lieu of the letters, other characters may be held within the holder, such as the numerals "16", or

if desirable, the holders may be made, such as is shown in the drawings, each holder being of an identical construction as the other. In other words, the numerals "16" are held between the holder which is constructed identically with the holders for the letters, as has been hereinbefore fully described. 35

What is claimed is:

An attachment of the class described, comprising a support, a base plate having up-bent and inturned marginal flanges at its longitudinal edges, indicia characters engaged under the flanges, the said flanges being struck between the indicia characters, whereby the same will be held separated and against displacement upon the base plate, means for fastening the base plate to the support, and fasteners passed through the base plate and such support between certain of said characters and having face plates carried thereby designating dots. 40

45 In testimony whereof I affix my signature 50. in presence of two witnesses.

EDWARD S. FITCH.
